CLAIM

We claim the ornamental design for a handle for a grill, as shown and described.

DESCRIPTION

FIG. 1 is a perspective view of a handle for a grill shown mounted on the lid of a grill, according to one embodiment.

FIG. 2 is a perspective view of the handle of FIG. 1.

FIG. 3 is a front elevation view of the handle of FIG. 1.

FIG. 4 is a rear elevation view of the handle of FIG. 1.

FIG. 5 is a side elevation view of the handle of FIG. 1.

FIG. 6 is a side elevation view of the opposite side of the handle shown in FIG. 5.

FIG. 7 is a top plan view of the handle of FIG. 1; and, FIG. 8 is a bottom plan view of the handle of FIG. 1.

The broken lines immediately adjacent the shaded areas represent the bounds of the claimed design while all other broken lines are directed to environment and are for illustrative purposes only the broken lines form no part of the claimed design.
